UNITED STATES PATENT OFFICE

VIRGIL E. WEEKS, OF KANSAS CITY, MISSOURI

BILLYFOLD

Application filed September 3, 1929. Serial No. 390,190.

My invention relates to improvements in bill folds.

The object of my invention is to provide a novel bill fold which is simple, cheap, light, compact, durable, not likely to get out of order, which will securely hold bills in compact form, which permits the ready and quick insertion or extraction of bills, and which is of an attractive appearance and convenient to carry.

The novel features of my invention are hereinafter fully described and claimed.

In the accompanying drawings, which illustrate the preferred embodiment of my improved bill fold,

Fig. 1 is a plan view, showing my improved bill fold in the stretched out or open position, a part being broken away.

Fig. 2 is an enlarged section on the line 2-2 of Fig. 1.

Fig. 3 is a perspective view of the clip, enlarged.

Fig. 4 is a reduced edge view of the bill fold with bills mounted therein.

Fig. 5 is a plan view, partly broken away of one end of the strip.

Fig. 6 is an enlarged plan view of a portion of the strip, a part of the clip and the spring, shown as before the channel member is mounted thereon.

Fig. 7 is a perspective view, enlarged, of the channel member.

Similar reference characters designate similar parts in the different views.

My improved bill fold comprises a strip composed of two pieces of flexible material, as leather, superposed one on the other and fastened together, as by stitching.

Between the two pieces of flexible material, designated by 1 and 2 at one end of the strip, is a reinforcing flat member 3.

Embracing opposite sides of the strip at the end having the member 3 is a channel member 4 having in its middle a notch 5

across which extends the free end of a spring wire 6 the other end of which has a lateral arm which extends into a notch 7 in the adjacent end of the strip. The portion of the spring wire 6 which extends across the notch 5 is flattened at 8, said flattened por-

tion 8 being embraced by one end of a clip 9, and is adapted to turn with a torsional movement when the free or other end of the clip 9 is swung away from the strip.

The free end of the clip 9 bears against that part of the strip containing the reinforcing member 3, and is adapted to hold with a spring pressure bills 10, Fig. 4, which are disposed in a pile on the strip.

When the clip and spring wire are first applied to the adjacent end of the strip, as shown in Fig. 6, the arm 11 of the spring wire is upwardly inclined, as shown in solid lines in Fig. 6. When the channel member 4 is applied to the strip the upper flange thereof engages said arm 11, and when the channel member is flattened from the form shown in Fig. 7, so as to embrace both sides of the strip, the arm 11 is depressed into the notch 7 of the strip, thus imparting a torsional tension to the spring wire 6 which tension causes the clip 9 to bear tightly at its free end against the strip, or against bills disposed between the clip and the strip. The arm 11 also, by being in the notch 7, serves to hold the spring wire 6 from longitudinal movement. The end of the clip 9 which embraces the spring wire 6 is disposed in the notch 5 of the channel member 4.

The clip 9 has between its ends a bend outwardly at 12, so that, when bills 10 are in the bill fold the contacting portion of the clip with the bills will be parallel, or substantially so, with said bills. As shown in Fig. 3, the inner side of the free end portion of the clip 9 may be roughened as with milling 13. For convenience in inserting bills, the free end portion of the clip 9 is slightly turned away from the strip, Figs. 2 and 4.

In the use of the bill fold, the bills 10 are slipped at one set of end portions between the clip 9 and the strip, the spring wire 6 serving to hold the clip firmly against the bills.

The strip and bills 10 may then be doubled or folded as shown in dotted lines in Fig. 4, thus disposing the bill fold with the included bills in compact and convenient form for carrying in the pocket.

I do not limit my invention to the struc-

ture shown and described, as modifications, within the scope of the appended claims, may be made without departing from the spirit of my invention.

5. What I claim is:—

1. In a device of the kind described, a strip of flexible material, a clip on the inner side and adjacent to one end of said strip having a free end portion adapted to extend over 10 and to press against said strip, a channel member embracing opposite sides of said strip at one end thereof and having a notch, the other end of said clip extending into said notch, and a spring in said channel member 15 having one end engaged by and held from turning by said channel member and having a portion extending across said notch and fastened to and adapted to swing with said clip and normally forcing said clip at the free 20 end of the latter toward said strip.
2. In a device of the kind described, a strip of flexible material, said strip having at one end portion a flat reenforcing member, said strip having at said end a notch, a channel member embracing opposite sides of said strip at said reenforced end portion and having a notch, a spring wire mounted in said channel member and having an arm extending into the notch in said strip, whereby the 25 spring wire is held from longitudinal movement in the channel member, said wire extending across the notch in said channel member and in that portion being adapted for torsional movement, said channel member holding said arm from turning, and a clip on the inner side of said strip having one end extending into said notch in said channel member and fastened to said torsional turning 30 portion of said spring, the latter normally exerting a pressure on the clip by which the latter is adapted to press against said strip in that portion containing said reenforcing member.

40 In testimony whereof I have signed my name to this specification.

VIRGIL E. WEEKS.
